[57] CLAIM

The ornamental design for a gravity feed telecommunications connector, as shown and described.

DESCRIPTION

FIG. 1 is a perspective view of the design of the invention; FIG. 2 is a left side view, the right side being a mirror image thereof;
 FIG. 3 is a front elevation view of FIG. 1;
 FIG. 4 is a rear elevation view of FIG. 1;
 FIG. 5 is a top plan view of the invention; and,
 FIG. 6 is a bottom plan view of the invention.
